UNITED STATES PATENT OFFICE.

ADOLFO LURIA, OF CHICAGO, ILLINOIS.

LITTER AND COLLAPSIBLE FIELD-COT.

1,164,828.

Specification of Letters Patent. Patented Dec. 21, 1915.

Application filed February 19, 1915. Serial No. 9,236.

To all whom it may concern:

Be it known that I, ADOLFO LURIA, a citizen of the United States, and a resident of Chicago, in the county of Cook and State 5 of Illinois, have invented a certain new and useful Improvement in Litters and Collapsible Field-Cots, of which the following is a specification.

My present invention relates generally to 10 litters and collapsible field cots, for army and domestic use, and more particularly to improvements in the character of apparatus described and claimed in my co-pending application, Serial Number 6375 which was 15 filed February 5, 1915.

More particularly the object of my present invention is to provide certain connections between the lateral braces of the frame and the legs, thereof utilized in the cot 20 formation, whereby the legs will be collapsed to positions adjacent and along the side bars of the frame by the collapsing movements of the lateral braces when the frame is folded.

25 Certain other changes in the details of construction will be apparent from the following description in which reference is made to the accompanying drawings, forming a part of this specification, and in 30 which—

Figure 1 is a top plan view of a litter constructed in accordance with the present invention, the parts being shown in litter formation. Fig. 2 is a view in side elevation of the litter. Fig. 3 is an end view thereof. Fig. 4 is a horizontal longitudinal sectional view therethrough. Fig. 5 is a cross sectional view through the litter. Fig. 6 is a view in end elevation showing the 40 litter folded. Fig. 7 is a bottom plan view of the litter with the parts in folded position.

Referring now to these figures, the side 45 bars 1 of the litter each comprise tubular sections 2 and 3, of which the section 3 telescopes into the section 2 and the inner end wall of the inner section 3 is formed with an opening 4, while the outer end wall of the section 2 is formed with an opening 5 alining with the opening 4, all as best seen in Fig. 4. Extending through these alined 50 openings 4 and 5 is a rod 6 having one end thereof fast within the opening 5 and the other end formed with a threaded nut 7 designed to limit the outward sliding move-

ment of the section 3 with respect to the section 2.

Formed on the section 2 of each of the side bars 1 adjacent to the outer end of such section, is a pair of collars 8, the collars of 60 each pair being spaced apart a suitable distance. Loosely surrounding each section 2, between the collars 8 thereon, is a sleeve 9, while fixed to the respective sections 3 adjacent to the outer ends thereof are sleeves 65 10. Each of the sleeves 9 and 10 is provided with a lug 11 extending laterally and inwardly of the frame, and pivotally connected at its outer end to the inner end of each of the lugs 11 is a lateral bracing 70 member or lever 12. The inner ends of the levers 12 of each pair are formed with laterally projecting pivot ears 13 in superposed relation and through the ears 13 are passed vertical pivot bolts 14. The lugs 13 75 of each pair of the levers 12 are preferably offset as best seen in Fig. 3 so that the shoulders thus formed on the levers will engage in the operative position, Fig. 1, whereby the levers are rigidly held against further movement.

Rigidly connected to the lower-ends of the pivot pins 15 extending vertically through the outer ends of the levers 12 and 11, are the upper horizontal portions of right angular brackets 16, while carried by the sleeves 9 and 10 are inwardly and downwardly projecting right angular brackets 17. The depending or vertical portions of the brackets 16 and 17 are spaced apart in 80 parallelism, and pivoted between the same are the upper extremities of legs 18, the lower ends of the legs 18 being formed with lateral projections constituting feet 19.

The upper end portion of each leg 18 is 95 formed with a toothed segment 20 that meshes with a similar segment 21 formed on the adjacent-outer extremity of the respective lever 12. These segments are disposed at right angles to each other owing 100 to the relative positions of the levers 12 and legs 18, and when the former are actuated to operative or extended position, the segments 21 meshing with the segments 20 swing the legs 18 to a vertical position so 105 as to support the litter above the ground for use as a cot, while when the levers 12 are actuated inwardly, incident to the folding of the cot, the segments 21 on the ends 110 of the respective levers 12 and in mesh with 115

the segments 20 swing the legs upwardly to a position substantially parallel with the side bars 1 so that the legs will be in an out-of-the-way position.

16 The canvas 22 spans the space between the side bars 1 and in the present instance, the portions of the side edges of the canvas 22 adjacent to the sections 2 are wrapped about such sections and the wrapped portions stitched to the main body portion as at 23. The remaining portions of the side edges of the support 22 are equipped with hooks 24 that engage in openings 25 in the sections 3 of the side bars, the hooks 24 and openings 25 forming detachable connections between the flexible support and the sections 3 so that this half of the flexible support may be folded onto the other half of the support when the litter is being folded or collapsed. The openings 25 in the sections 3 adjacent to the inner ends thereof are preferably so positioned as to be disposed immediately adjacent to the inner ends of the sections 2 when the sections 3 20 are withdrawn from the sections 2 so that the hooks 24 that engage in said openings will abut the adjacent ends of the sections 2 and so prevent the accidental sliding of the inner sections into the outer sections in 25 the use of the litter.

In practice when the component parts of the device are in litter or cot formation, the sections 3 are withdrawn from the sections 2 and the levers 12 are opened to hold the side bars properly spaced apart, while the legs depend below the side bars to support the litter and the hooks 24 engage in the openings 25, thereby enabling a person to be supported at full length above the ground. 30 The outer ends of the side bars 1, that is, the ends of the bars beyond the sleeves 9 and 10, constitute handles whereby the litter or cot may be lifted and carried about from place to place when in use. To collapse the frame, the hooks 24 are disengaged from the openings 25 and this half of the canvas 22 folded onto the remaining half thereof secured to the side bar sections 2. The sections 3 are now slid into the sections 2 to 35 diminish the length of the frame and when this is done, the inner joints at 14 between the levers 12 are broken and the side bars moved toward each other to reduce the width of the frame. In this latter movement of the side bars, the meshing segments 21, 20, swing the legs to elevated position, and owing to the positions of the lugs 11, the legs and brackets lie within the plane of the side bars 1, so that any number of 40 folded litters may be placed one upon the other for shipping or storage purposes.

It will be noted that when the parts are in litter or cot formation, the inner connected ends of the levers 12 pass the line between the pivotal connections of the levers

and the lugs 11 with the effect to lock the levers in such position so that accidental closing of the litter is prevented.

Succeeding the folding or collapsing of the frame, as just described, the sections 2 70 of the side bars are revolved so as to take up any slack in the canvas 22 and provide a comparatively small compact article which may be readily and conveniently carried about on the back.

In the present instance, the lower face of the section of the canvas 22 that is fixed to the sections 2 of the side bars, is equipped with a pocket 26 designed to receive medicine, surgical instruments, or analogous necessary articles.

From the foregoing description taken in connection with the accompanying drawings, the construction and manner of assembling my improved litter will be readily apparent, as well as the advantages it provides over the several constructions described and claimed in my application above referred to.

I claim:

1. A combined litter and field cot, comprising side bars formed of telescoping sections, a canvas spanning the space between said side bars and having a portion thereof fixed to certain opposing sections of said side bars and the remaining portion detachably connected to the other sections of the said side bars.

2. A combined litter and field cot comprising side bars each formed of telescoping sections, a canvas spanning the space between said side bars and having a portion thereof fixed to certain opposing sections of said side bars and the remaining portion detachably connected to the remaining sections of the side bars, said fixed portion of the canvas having a lower pouch or pocket, for the purpose described.

3. A combined litter and field cot comprising side bars each formed of telescoping sections, a canvas spanning the space between said side bars and having a portion thereof fixed to certain opposing sections of said side bars and the remaining portion detachably connected to the remaining sections of the side bars, said first-named opposing sections of the side bars to which a portion of the said canvas is fixed, being rotatable with respect to the other section, whereby portions of the canvas may be 110 rolled on the said opposing sections of the side bars when the latter are moved together in collapsed position.

4. A combined litter and field cot comprising side bars, a canvas extending between said side bars, bracing levers pivotally connected to one another and to the said side bars whereby to hold the latter in spaced relation in operative position, legs depending from and having connection with 125

the said side bars, and connection between the bracing levers and the legs whereby to move the latter to position adjacent to and along the side bars when the former are 5 moved to permit the side bars to be moved toward one another in folded position.

5. A combined litter and field cot comprising side bars, a canvas extending between said side bars, bracing levers pivotally connected to one another and to said side bars adjacent the extremities of the latter, whereby to hold the side bars spaced apart, legs pivotally connected to, and depending from, said side bars adjacent the 10 ends thereof and capable of swinging movement from vertical to horizontal position, and vice versa, and connections between said legs and said bracing levers whereby to swing the legs from one position to the other when the said levers are swung to and from operative position.

6. A combined litter and field cot comprising side bars in telescoping sections, a canvas extending between said side bars, sleeves carried by the sections of the side bars and having upper inwardly projecting lugs and also having lower inwardly and downwardly projecting lugs, bracing levers pivotally connected to one another at their inner ends and pivotally connected at their outer ends to the upper lugs, legs pivotally connected at their upper ends to the said inwardly and downwardly projecting lower lugs, and relatively engaging toothed segments carried by the upper ends of the legs and the outer ends of the said bracing le- 15 20 25 30 35

vers, whereby to swing the legs to vertical and horizontal positions respectively when the said bracing levers are moved to operative and inoperative position. 40

7. A combined litter and field cot comprising side bars in telescoping sections, a canvas extending between said side bars, sleeves carried by the sections of the side bars and having upper inwardly projecting lugs and also having lower inwardly and downwardly projecting lugs, bracing levers pivotally connected to one another at their inner ends and pivotally connected at their outer ends to the upper lugs, legs 45 50 55 60 65 pivotally connected at their upper ends to the said inwardly and downwardly projecting lower lugs, and relatively engaging toothed segments carried by the upper ends of the legs and the outer ends of the said bracing levers, whereby to swing the legs to vertical and horizontal positions respectively when the said bracing levers are moved to operative and inoperative position, certain of the sections of the side bars being rotatable with respect to their said sleeves, and having the canvas fixed thereto whereby portions of the canvas may be rolled upon the said sections of the side bars by their rotative movement when the bracing levers are moved to inoperative position, and the side bars folded to positions adjacent one another. 65

ADOLFO LURIA.
